UNITED STATES PATENT OFFICE.

AUGUST A. GASSINGER, OF BALTIMORE, MARYLAND.

WINDOW SCREEN.

Application filed July 25, 1921. Serial No. 487,391.

To all whom it may concern:

Be it known that I, AUGUST A. GASSINGER, citizen of the United States, residing at Baltimore, in the county of Baltimore and State 5 of Maryland, have invented certain new and useful Improvements in Window Screens, of which the following is a specification, reference being had therein to the accompanying drawing.

10 My invention relates to new and useful improvements in screens and more particularly to a window screen of the roller type wherein the screening is wound upon a spring controlled roller.

15 The primary object of the invention is the provision of such a screen which is adapted for use in connection with windows of various heights and widths, the roller upon which the screening is wound being adjustable as to length and the spring thereof being so constructed and connected as to normally hold the screening wound upon the roller and being placed under tension when the screening is unwound.

20 25 A further object consists in the provision of novel means for engaging a transversely disposed bar carried by the screening for holding said screening, unwound from the roller, over the window opening, and novel 30 means for engaging the longitudinal vertical edges of the screening to provide against the displacement of the screening and to prevent openings through which flies or other insects might pass.

35 40 It is a still further object to provide a shield, either carried by the screen or by the window sash, to prevent flies, or other insects from entering between the screen and window sash, the shield, if carried by the screen, engaging the sash to close openings and if carried by the sash engaging the face of the screen for the same purpose.

45 With the above and other objects in view, which will appear as the description proceeds, my invention consists of the novel details of construction and arrangement of parts described in the following specification and illustrated in the accompanying drawings, and while I have illustrated and 50 described the preferred embodiments of the invention it will be understood that such changes may be made as will follow within the scope of the appended claims.

55 In the drawings:—

Fig. 1 is a front elevation with parts broken away.

Fig. 2 is a vertical section with parts shown in elevation.

Fig. 3 is a horizontal section.

Fig. 4 is a fragmental longitudinal section, through the spring controlled roller, with parts shown in elevation.

Fig. 5 is a top plan of one of the side rails showing in full line the retaining plate in raised position.

Fig. 6 is a top plan of a slightly modified form of side rail with the retaining plate shown in full line in operative position and, in dotted lines in raised position.

Fig. 7 is a fragmental plan of one of the plates from which the side rail is made.

Fig. 8 is a fragmental plan of the blank from which the bar for the lower end of the screening is made.

Fig. 9 is a fragmental perspective of one of the retaining plates, and

Fig. 10 is a fragmental side elevation showing a slightly modified form of attachment for preventing flies or other insects from entering between the screen and window sash.

In the drawings 1 indicates the window frame and 2 the window sash, each of ordinary and any well-known construction, and A and B are vertical extending side rails going forward to make up the frame of my screen, each of the said side rails being of angle iron construction forming the right angle extending arms 3 and 4, the arms 3 adapted to engage the sides of the window frame 85 and the arms 4 extending a short distance over the window openings, as clearly shown in the drawings. The side rails are secured to the window frame by means of the screws 5 or other suitable fasteners which pass through openings formed in the arms 3 and engage in the frame. The outer edges of the arms 3, of the side rails, preferably extend a short distance beyond the face of the window frame for a purpose which will later 90 appear.

A roller 6 is carried by, and maintained between the side rails A and B, adjacent the upper ends, said roller provided in one end with a longitudinal extending recess 7 which is adapted to receive a rotatable spindle 8, the outer end of which is elongated, as shown at 9 to be received in an elongated opening formed in the arm 3 of the side rail A. A coil spring 10 is received in the recess 7, and surrounds the spindle 8, one end of said coil spring being connected to the spindle at 110

and the opposite end being connected to a bar 12, or other suitable projection, secured in the recess 7. The opposite end of the roller receives a screw threaded spindle 13, the outer end of which is reduced and round, as shown at 14, said reduced round end 14 adapted to be received in a round opening formed in the arm 3 of the side rail B. The spindle 13, adjacent the outer end, is 10 provided with a square shoulder 15 adapted to be engaged by a wrench or similar instrument for adjusting the spindle with respect to the end of the roller, said adjustment adapting the roller to be used with windows of various widths. Screening 16 is secured to and adapted to be wound upon the roller 6, the screening being of any desired type although I preferably use a cloth fabric as this will more readily wind upon the roller than will 20 the wire screening. To the outer edge of the screening I attach a transversely disposed bar 17, said bar being preferably constructed of metal adapted to be bent into U-shaped form to engage over the edge of 25 the screening and secured thereto by the prongs 18, struck from one arm of the shield, and which pass through the screening and engage through openings formed in the opposite arm. A finger piece 19 is struck from 30 the bar and extends at right angles thereto so that it may be easily grasped for operating the screen.

To each of the side rails A and B I hingedly connect plates 20, preferably by means 35 of coiled springs 21, one end of the springs being connected to the arm 3 of the rail at 22 and the opposite end being connected to the plate 20 at 23, I use a plurality of these coil springs 21, vertically spaced, so as to normally hold the plates 20 against the face of 40 the arm 4 of the side rail. At the lower end the plates 20 are provided with an offset position 24 forming a recess for the reception of the transversely extending bar 45 17, of the screening, when the said screening is unwound from the roller and covers the window opening. It will be understood that when the screening is unwound the longitudinal vertical edges thereof will engage 50 over the faces of the arms 4 of the side rails A and B and be tightly held there against by the spring pressed plates 20. When the screening is to be wound or unwound it will be necessary that the plates 55 20 be raised from engagement with the arms of the side rails and in order to hold the said plates raised, against the tension of the springs 21, I provide the catches 26 which are pivotally connected to the plates 20 at 60 26', the outer ends of the catches being of U-shaped construction so as to engage over the edges of the arms 3 of the side rails.

In order to prevent flies, or other insects, 65 from entering between the screen and window sash I secure a bar 27 transversely

across the sash in position to engage the face of the screen.

In Fig. 6 I have shown a slightly modified form of spring for connecting the plate 20 to the side rail. In this form of the invention instead of using the coil springs 21 I use the flat springs 28 which are of right angle construction and adapted to be secured to the arm 3 of the side rail and to the plate 20 by means of the rivets 29 or 75 other suitable fastening means.

In Fig. 10 I have shown a slightly modified form of shield or guard for preventing insects from passing between the screen and sash. In this modified form the shield or guard is in the form of a curved plate 30 adapted to extend over the top of the roller 6, between the side rails A and B and is provided with an extension 31 extending 80 downwardly at an angle to engage the face of the window sash. As clearly shown in the drawings, this shield or guard 30 will merely be hung over the roller, in engagement with the window sash, by the extension 31, so as to engage the upper edges of the 85 arms 3 of the side rails.

From the above detail description it is thought that the construction as well as the manner of using my screen will be clearly 90 understood. It will be seen that in reality the screen frame is merely composed of the side rails A and B and by this construction the screen is adapted to windows of various widths and the spring controlled roller may 95 be adjusted by the adjustable screw thread spindle 13, to adapt itself to various sizes of windows. In order to adjust the roller the square shoulder 15 on the spindle 13 may be engaged by any suitable form of 100 wrench or other implement. The spring roller 6 is so constructed as to normally hold 105 the screening 16 wound thereon and when the screening is unwound the spring will be placed under tension. The plates 20 will 110 be normally held in engagement with the arms 4 of the side rail by the springs and when it is desired to unwind the screen to cover the window openings, the said plates will be raised to extend parallel with the 115 arms 3 of the side rails. The plates are held in this raised position by the catches 26 which, as described, engage the outer edges of the arms 3. When the screening has been unwound to cover the opening the 120 catches 26 are disengaged from the arms 3 and the springs will force the plates 20 back into original position to securely hold the longitudinal vertical edges of the screening 125 between the arms 4 of the side rails and the plates 20. When the screen is in lowered position the transversely disposed bar 17 will be received in the off set portions 130 of the plates 20, said off set portions engaging the bar to prevent the spring controlled roller from overcoming the pressure 135

of the plates 20 to wind the screen. It will be further seen that I have provided means for preventing insects from entering between the window sash and screen, two different forms of shield or guard being disclosed in the drawings.

As described, above, the screening 16 is preferably of cloth fabric as this will more readily wind upon the roller than will wire screening and, of course, it will be understood that when cloth fabric is used it will necessarily have to be of a water proof construction. I do not desire to limit myself to any particular construction or form of screening, but in experimenting I have found that wire fabric will not tightly wind upon the roller but instead will have a tendency to spread out, thus forming a very bulky roll.

Having fully described my invention what I claim as new and desire to secure by Letters Patent is:

1. A mounting for a roller carried screen comprising an angle iron frame, a plate hingedly connected to the frame for engaging the longitudinal edges of the screening when the same is unwound from the roller,

and means carried by the plate and adapted to engage over the edge of the frame for holding the plate away from the screening. 30

2. A mounting for a roller carried screen comprising an angle iron frame, a plate hingedly connected to the frame for engaging the longitudinal edge of the screening when the same is unwound from the roller, 35 and a catch pivotally connected to the plate and adapted to engage over the edge of the frame for holding the plate away from the screening.

3. A mounting for a roller carried screen 40 comprising an angle iron frame, a plate hingedly connected to each side of the frame, springs for normally holding the plates in engagement with the sides of the frame for clamping the screening therebetween, when unwound from the roller, and catches pivotally connected to the plates and adapted to engage over edges of the sides of the frame for holding them away from the screening. 45

In testimony whereof I hereunto affix my signature.

AUGUST A. GASSINGER.
